(57) **CLAIM**

The ornamental design for a dual dunnage hanger bag, as shown and described.

DESCRIPTION

FIG. 1 is a top perspective view of a dual dunnage hanger bag, showing our new design in a condition of use with cargo;

FIG. 2 is a top perspective view thereof, illustrated with the cargo omitted;

FIG. 3 is an exploded perspective view thereof;

FIG. 4 is an alternative exploded rear elevational view of the dual dunnage hanger bag;

FIG. 5 is an exploded left-side elevational view of the dual dunnage hanger bag of FIG. 4, the right-side elevational view being a mirror image thereof;

FIG. 6 is an exploded top plan view of the dual dunnage hanger bag of FIG. 4; and,

FIG. 7 is an exploded bottom plan view of the dual dunnage hanger bag of FIG. 4.

The broken lines in FIG. 1 depict environmental matter that forms no part of the claimed design.

1 Claim, 7 Drawing Sheets
